S. A. CRONE
RAILWAY BRAKE BEAM
Filed June 6, 1923

INVENTOR:
Seth A. Crone
BY
Charles L. Gill,
ATTORNEY.

UNITED STATES PATENT OFFICE.

SETH A. CRONE, OF EAST ORANGE, NEW JERSEY.

RAILWAY BRAKE BEAM.

Application filed June 6, 1923. Serial No. 643,626.

To all whom it may concern:

Be it known that I, SETH A. CRONE, a citizen of the United States, and a resident of East Orange, in the county of Essex and State of New Jersey, have invented certain new and useful Improvements in Railway Brake Beams, of which the following is a specification.

The invention pertains to trussed brake-beams for railway cars and especially to a novel strut interposed between the compression and tension members of the beam.

One purpose of the invention is to provide in a single folded or U-ed forged metal bar, a novel one-piece strut having at the front end thereof a seat, integral with the strut, to receive the middle portion of the tension member of the beam and also having at said end forwardly projecting oppositely disposed arms, integral with the strut, serving to deepen said seat and ensure the retention of the truss-rod thereon. The aforesaid arms are cut from diagonally opposite edge portions of the forged bar at or adjacent to the transverse middle part thereof whereat the U-bend or fold is to be or is formed, and said arms are bent forwardly to lie at the upper and lower sides of the truss-rod seat and extend above and below the middle portion of the truss-rod.

The invention will be understood from the detailed description hereinafter presented, reference being had to the accompanying drawings, in which:

Fig. 1 is a vertical longitudinal section through a brake beam embodying my invention, the strut being shown in side elevation;

Fig. 2 is an end projection of the strut taken from the right hand end of Fig. 1, a portion of the truss-rod being indicated by dotted lines;

Fig. 3 is a plan view of the forward portion of the strut, the truss-rod being indicated by dotted lines;

Fig. 4 is a plan view of the middle portion of the forged metal bar from which the strut is formed and illustrates the first step in the process of creating a seat for the truss-rod, said step consisting in cutting and bending downwardly from diagonally opposite

edge portions of the bar, reversely disposed, approximately triangular, sections which finally become the aforesaid arms constituting portions of the truss-rod seat and extending above and below the middle portion of the truss-rod, and

Fig. 5 is an edge view of the same.

In the drawings 10 designates the strut, 11 the compression member and 12 the tension member comprising a trussed brake-beam for railway-cars.

The strut is formed from a single bar of forged metal folded at its middle portion into approximately U-shape having parallel sides 13, 14 and members, as 15, for illustration, at the free ends of said sides to engage the compression member, which may be of any suitable cross-section. By suitably twisting the sides 13, 14 at their rear portions, as at 16, in a well understood manner, the main body of said sides is caused to lie at an angle of forty degrees to the vertical, as shown in Figs. 1 and 2, to suitably receive the brake-lever, not shown, as usual.

My invention resides in a special formation of the forward end of the strut to adapt the same to adequately receive and retain the middle portion of the truss-rod.

In the transverse portion or fold at the front end of the strut is formed a horizontally extending convex bearing-seat 17 having concave surfaces to receive the middle portion of the truss-rod 12, and this bearing-seat is formed, in part, by insetting along a diagonal line across the folded end of the bar, a suitable width of said fold to take the truss-rod and which width extends horizontally in the finished strut, and, in part, by projecting forwardly the arms 18, 19 to lie at the upper and lower sides of said seat and extend forwardly above and below the truss-rod, as shown in Fig. 1, said arms constituting portions of the upper and lower sides of the seat 17 and being integral with the other portions of the strut.

In carrying out my present invention I do not have to depress inwardly the metal of the U-bend to form the truss-rod seat, to a very great or to any inconvenient extent, since I deepen said seat and effectually retain the truss-rod thereon by means of said

forwardly projecting integral arms 18, 19 which embrace the upper and lower sides of said rod.

The arms 18, 19 are reversely disposed but otherwise correspond with each other, and said arms are formed from sections 20, 21 of tapered or approximately triangular outline cut from diagonally opposite edge portions of the middle part of the forged metal bar whereat said bar is to be folded to constitute the sides of the strut, as shown in Figs. 4 and 5. The sections 20, 21 are cut on inwardly slanting reverse lines 22, 23 and bent downwardly from the flat bar at a single operation, and thereafter the bar is folded or U-ed upwardly on the straight transverse width 23' thereof extending across the bar between the inner ends of the cut-lines 22, 23 and defined by the parallel dotted lines 24. The folding or U-ing of the bar leaves the transverse fold-end thereof rounded or convex on its outer surface, with the sections 20, 21 projecting from diagonally opposite corners of said end.

The folded bar is then subjected to dies to form the concave seat 17 hereinbefore described and bend the cut sections 20, 21 forwardly at the upper and lower sides of said seat to constitute the reversely extending arms 18, 19.

In Figs. 2 and 3, the surface 25 is that which is left after the arm 18 has been cut and bent forwardly at the forward end of the strut, this surface in edge view also being shown at 25 in Fig. 1. In Fig. 1 the dotted line 26 denotes the normal outer edge of the side member 13 from which the arm 18 was cut and bent forwardly leaving the exposed surface 25.

In Figs. 1 and 2, the surface 27 is that which is left after the arm 19 has been cut and bent forwardly at the forward end of the strut. In Fig. 1 the dotted line 28 denotes the normal outer edge of the side member 14 from which the arm 19 was cut and bent forwardly, leaving the exposed surface 27.

The seat 17 is convexed horizontally, as indicated by the dotted line in Fig. 3, to receive the curved middle portion of the horizontal truss-rod and said seat is concaved on vertical lines to receive the vertical convex surface of said rod.

In forming the seat 17 on the fold-end of the bar, I bend forwardly the sections 20, 21 to form the final arms 18, 19 and at the same operation bend forwardly on curved lines those transverse diagonally opposite portions of the fold-end of the bar which are immediately adjacent to and more directly carry the inner and broader ends of the sections 20, 21 and hence the seat is formed in part by concaving forwardly diagonally opposite corner portions of the fold-end of the bar and in part by, at the

same operation, setting the sections 20, 21 forwardly and inwardly to form the arms 18, 19. The treatment just described of the fold-end of the bar results in the formation of a truss-rod seat of exceptional efficiency and in the arms 18, 19 and adjacent portions of the end of the strut having a maximum horizontal extension along the upper and lower sides of the truss-rod, as shown in Fig. 2, in which it may be seen that the arm 18 extends across the longitudinal plane of the strut-side 13 and that the arm 19 correspondingly extends across the longitudinal plane of the strut-side 14. In Fig. 3 it may be seen that the arms 18, 19 point in opposite directions and retain their tapered or approximately triangular outline and that said bars are caused to extend laterally from the fact that the adjacent transverse portions of the fold-end of the bar carrying said arms are turned forwardly and inwardly on curved lines, thereby turning said arms to present their outer side edges forwardly.

In the manufacture of the strut, my experience is that the flat bar should be subjected to the step indicated in Figs. 4 and 5, and then folded or U-ed and that the seat formation at the forward end of the strut should be formed on the folded bar by a single operation, as distinguished from U-ing the bar and forming the seat by a single operation.

What I claim as my invention and desire to secure by Letters Patent, is:

1. A brake-beam strut in one integral bar of forged metal folded to form a U-bend at the forward end of the strut and having parallel angularly set spaced-apart sides connected together by said forward fold, the forward end of the strut at said fold being inset on a line horizontally crossing the forward ends of said angularly set sides to form a seat for a truss rod, and said end of the strut having arms integral therewith extending forwardly above and below said seat to deepen the same and retain the truss rod thereon, said arms being composed of sections slit from diagonally opposite portions of the forward end of the strut and bent forwardly to lie above and below the truss rod.

2. A brake-beam strut in one integral bar of forged metal folded to form a U-bend at the forward end of the strut and having parallel angularly set spaced-apart sides connected together by said forward fold, the forward end of the strut at said fold being inset on a line horizontally crossing the forward ends of said angularly set sides to form a seat for a truss rod, and said end of the strut having arms integral therewith extending forwardly above and below said seat to deepen the same and retain the truss rod thereon, said arms being composed of reversely tapered sections slit from diagonally

- opposite portions of the forward end of the strut and, with the immediately adjacent diagonally opposite corner portions of said fold, bent forwardly to lie above and below 5 the central horizontal plane of the truss rod.
3. A brake-beam strut in one integral bar of forged metal folded to form a U-bend at the forward end of the strut and having parallel angularly set spaced-apart sides connected together by said forward fold, the forward end of the strut at said fold being inset on a line horizontally crossing the forward ends of said angularly set sides to form a seat for a truss rod, and said end of the 10 strut having arms integral therewith extending forwardly above and below said seat to deepen the same and retain the truss rod thereon, said arms being composed of sections slit from diagonally opposite portions 15 of said sides adjacent to and having their broader ends at said fold, and said arms and the immediately adjacent portions of the fold being bent forwardly to embrace the truss rod.
- 20 4. A brake-beam strut in one integral bar of forged metal folded to form a U-bend at the forward end of the strut and having parallel angularly set spaced-apart sides connected together by said forward fold, the forward end of the strut at said fold being concavely inset on a line horizontally crossing the forward ends of said angularly set sides to form a seat for a truss rod, and said end of the strut having arms integral therewith 25 extending forwardly above and below said seat to deepen the same and retain the truss rod thereon, said arms being approximately triangular in outline and composed of reversely tapered sections slit from diagonally 30 opposite portions of said sides and bent forwardly to extend above and below the middle portion of said seat.
5. A brake-beam strut in one integral bar of forged metal folded to form a U-bend at the forward end of the strut and having parallel angularly set spaced apart sides connected together by said forward fold, the forward end of the strut at said fold being inset on a line horizontally crossing the forward ends of said angularly set sides to form a seat for a truss rod, and said end of the strut having arms integral therewith extending forwardly above and below said seat and pointing in reverse directions to deepen the 45 seat and retain the truss rod thereon, said arms being composed of reversely tapered portions slit on inwardly inclined reverse lines from diagonally opposite edges of the forward end of the strut and bent forwardly 50 to lie above and below the truss rod.
6. A brake-beam strut in one integral bar of forged metal folded to form a U-bend at the forward end of the strut and having parallel angularly set spaced-apart sides 55 connected together by said forward fold, the forward end of the strut at said fold being horizontally convexed to seat the middle portion of a truss-rod and having means thereat for retaining said rod on its seat, said means comprising arms slit from diagonally opposite portions of the forward end of the strut and bent forwardly to extend above and below portions of the truss-rod.
7. A brake-beam strut in one integral bar of forged metal folded to form a U-bend at the forward end of the strut and having parallel angularly set spaced-apart sides connected together by said forward fold, the forward end of the strut at said fold being horizontally convexed to seat the middle portion of a truss-rod and having means thereat for retaining said rod on its seat, said means comprising in part a concave surface formed on said seat adapted to the convex surface of said rod and in part of arms slit from diagonally opposite portions of the forward end of the strut and bent forwardly to extend above and below portions of the truss-rod.
8. A brake-beam strut in one integral bar of forged metal folded to form a U-bend at the forward end of the strut and having parallel angularly set spaced-apart sides connected together by said forward fold, the forward end of the strut at said fold being horizontally convexed to seat the middle portion of a truss-rod and having means thereat for retaining said rod on its seat, said means comprising arms slit from diagonally opposite corner portions of the strut at the forward fold thereof and transverse portions of said fold at and carrying said arms, said transverse portions of said fold and said arms being bent forwardly to embrace the truss rod at the upper and lower 100 sides thereof.
9. A brake-beam strut in one integral bar of forged metal folded to form a U-bend at the forward end of the strut and having spaced-apart sides connected together by said forward fold, the forward end of the strut at said fold being inset on a line horizontally crossing the forward ends of said sides to form a seat for a truss rod, and said end of the strut having arms integral therewith extending forwardly above and below said seat to deepen the same and retain the truss rod thereon, said arms being composed of sections slit from the forward portion of the strut and extended forwardly to lie 105 above and below the truss rod.
10. A brake-beam strut in one integral bar of forged metal folded to form a U-bend at the forward end of the strut and having spaced-apart sides connected together by said forward fold, the forward end of the strut at said fold being inset on a line horizontally crossing the forward ends of said 110

2
sides to form a seat for a truss rod, and said end of the strut having arms integral therewith extending forwardly above and below said seat to deepen the same and retain the truss rod thereon, said arms being composed of sections slit from diagonally opposite corner portions of the forward end of the

strut and extended forwardly to lie above and below the truss rod.

Signed at New York city, in the county 10
of New York, and State of New York, this
4th day of June, A. D. 1923.

SETH A. CRONE.
